UNITED STATES PATENT OFFICE

HARRY GAIL KREIS, OF CLEVELAND, OHIO

SLIDE HAMMER

Application filed January 26, 1932. Serial No. 589,022.

An essential object of the present invention is the delivery of a maximum stress under the blow of a sliding hammer and incident thereto to the elimination of binding and frictional 5 resistance to the sliding movement of the hammer.

Another object is the provision of parts affording such an anchorage to the part to be stressed that substantially direct stress is delivered through the hammer blow be directed 10 to the withdrawal of the object acted upon.

In greater detail, the objects of the present invention include provision for effective access to parts otherwise not easily accessible, 15 and the exertion of hammer blow withdrawing strains on such parts on lines substantially coincident with the longitudinal axis of the hammer.

With these and further objects in view as 20 will in part hereinafter become apparent and in part be stated, the invention includes a reciprocating hammer, a guiding rod therefor, and means carried by the rod for engaging a part to be withdrawn in position for 25 locating such part with the line of its travel substantially coincident with and continuous of the line of movement of the hammer in approaching the blow-delivering position.

The invention further includes in such a 30 combination the employment of an offset portion to facilitate such alinement, and still further includes thin, pronged bifurcations for facilitating application in otherwise inaccessible positions.

The invention also includes the provision 35 for obtaining the results of the combinative action of a sliding hammer engaging a hammer rod, the two being shaped relative to each other for enabling the hammer to slide 40 on longitudinal edges so as to afford only the resistance of a minimum number of lines of contact and thus avoid both frictional resistance of sliding action and likelihood of retardation by binding action.

The invention still further comprises certain other novel constructions, combinations, and arrangements of parts as subsequently 45 specified and claimed.

In the accompanying drawing,—

50 Figure 1 is a view in side elevation of a

slide hammer embodying the features of the present invention in one of the simpler forms.

Figure 2 is an end view thereof looking at the jaw end with the coupling sleeve of the embodiment of Figure 6 illustrated as applied. 55

Figure 3 is a transverse, horizontal section through the hammer member and the bar on which it is mounted with the hammer member centered with respect to the bar. 60

Figure 4 is a similar view of the same with the hammer member in that sliding contact ordinarily assumed during a stroke of the hammer. 65

Figure 5 is an enlarged, detailed, fragmentary, sectional elevation showing the integral formation of the hammer-blown-receiving terminus or knob on that end of the slide hammer rod opposite to the jaw. 70

Figure 6 is a view similar to Figure 1 of 75 a further embodiment of the invention including features providing for the detachable mounting of the jaw.

Figure 7 is a longitudinal, vertical section through the retaining sleeve of the parts seen in Figure 6, the coupled ends of the rod and jaw being seen in elevation. 75

Figure 8 is a detailed, fragmentary perspective view of the coupling end of the rod or jaw. 80

Figure 9 is a view similar to Figure 3 of a slightly modified embodiment wherein the lines of contact are provided by the polysided bore of the handle as the reverse of the polysided rod. 85

In the industrial art of slide hammers, it has been common practice to provide a rod and a hammer slidingly mounted thereon and retained against detachment from the rod with parts so constructed and located as to enable the hammer to contact after sliding movement and thereby deliver a hammer blow to the contacted part, which part is customarily either the rod itself or a detent carried thereby, and such common practice has included the employment of projecting claws and return hooks. In the return hook type, it has been proposed to employ the hook for withdrawing objects, such as cotter pins, under hammer blows, 100

but in the instances of such proposed arrangement the hook has been offset laterally of the shaft or rod, and the withdrawing stress has, therefore, been delivered not only 5 off-center but subject to a certain degree of torque incident to the off-center condition which largely detracts from the force of the withdrawing or retractile blow, so that the proposed devices have not been adapted 10 heretofore to the removal of parts requiring a very substantial stress for detachment, such as the removal of frozen or seized gears, nor has any provision heretofore been proposed, so far as known to me, for adapting 15 the hook or other parts of a slide hammer for engagement with any such gears or like parts offering but a minimum opportunity of accessibility and requiring very substantial stress for removal. The present invention 20 provides facilities for adapting a slide hammer for effective use in the removal of difficultly accessible parts requiring substantial stresses for detachment.

Referring to the drawing by numerals, 1 25 indicates a rod on which the sleeve-like hammer 2 is slidingly mounted. At or adjacent one end of the rod 1 is a stop 3 for the hammer 2, which stop may be any appropriately constructed shoulder outstanding from the rod 1 in a manner to deliver to the rod hammer blow stresses received by the shoulder. 30

The shoulder 3 is preferably in the form of an integral knob produced on the end of 35 the rod 1 by swaging, as by the operation of a machine quite similar to that commonly employed as a header for screws and nails. It has heretofore been proposed in slide hammer construction to apply a nut 40 threaded onto the hammer shaft to receive the blows of the slide hammer, but my experience over a wide range of actual practice has convinced me that threads will not endure continued or repeated use as the 45 shocks and stresses invariably and all too soon either strip the threads or crystallize them, or otherwise cause the nut to loosen and come off, and I myself have proposed heretofore to anchor a shoulder or knob corresponding to the knob 3 by swaging a 50 reduced shank of the rod extending through the knob, but even this latter construction has not been satisfactory and in some instances has given way and allowed release 55 of the knob. Obviously, as soon as the knob is detached from the rod or shaft of the hammer, the hammer becomes utterly useless for its intended purpose. Thus, I find the 60 integral formation of the shaft, as by the swaging of a knob 3, the most dependable and most nearly permanent mode of construction. In this connection, however, it will be noted that the hammer 2 cannot be applied onto the hammer rod after the head 65 or knob 3 has been formed when the parts

are constructed as seen in Figure 1, because of the obstruction at the opposite end of the rod, and when the hammer is constructed as seen in Figure 1, special provision must be made for accommodating the inconvenience 70 of the presence of the hammer 2 on the rod during the swaging up operation which produces the knob 3. This difficulty is overcome in the embodiment seen in Figure 6, as will be later pointed out. 75

At the opposite end of rod 1 from knob 3, the material of the rod is flattened to a thinness affording adaptability for introduction into slots, spaces or openings which are relatively thin, and the flattened portion is bent 80 laterally in the form of prongs 5, 5, the said terminal portion being bifurcated to provide a tapering opening 6 producing a jaw adapted to receive the body of parts to be acted on, such as the body of a bolt, shaft, screw or nail. The thin-pronged, bifurcated, laterally-extending portion 5 is preferably set approximately at right angles to the line of the rod 1, and the loop or offset portion 4 is sufficiently deep to allow the head or engaged portion of the work which is to be removed to extend across the projected longitudinal axis of rod 1, whereby hammer stresses exerted on such work will be delivered substantially in the line of and continuous of the corresponding axis of such work. (See Figure 2.)

As clearly seen from Figures 3 and 4, the bore of hammer 2 through which the rod 1 100 extends is cylindrical, so that at all places it presents a curved surface to the rod and the rod being polysided presents the meeting edges of its several faces as spaced lines for contact. It should be apparent, particularly 105 from Figure 4, that the curved surface of the bore of hammer 2 cannot contact with more than two of these lines at one time, and thus the frictional resistance of one body sliding upon another is reduced to the absolute minimum. The bore is made sufficiently large for 110 free play of the hammer on the rod, but the fact that curved surfaces engage mere longitudinal lines of contact precludes any such binding action as frequently occurs where a 115 cylindrical sleeve rides on a cylindrical rod and is tilted laterally relative to the rod. Furthermore, the curved wall of the bore of the hammer is not only spaced from all parts of the rod except for the two lines of contact during actual operation but from time to time the said curved walls naturally contact at different places so that there is no likelihood of the wearing of grooves into the 120 wall of the bore of the hammer. Furthermore, the rod 1 and its connected parts as above described, and the hammer are all carefully tempered to give them both the required toughness for enduring the service intended and also the required hardness for 125 130

preventing such wear as to appreciably increase the width of the lines of contact between the sleeve hammer and the rod.

In this connection it should be borne in mind that as a matter of inexpensiveness and convenience of manufacture, the rod 1 is made polysided while the sleeve 2 has its bore formed cylindrical or otherwise curved to give the desired result. Of course, the actual 10 number of sides of rod 1 may be varied to any extent, so long as mere lines of contact are provided for the sliding engagement of the sleeve hammer and wide surface contact is accordingly avoided. In Figure 9 is seen the 15 slide sleeve hammer 2a mounted on the slide hammer rod 1a, the rod being cylindrical instead of polysided, and the bore of the hammer being provided with the edges affording the individual and narrow lines of contact, as 20 by forming a polysided bore 2b within the sleeve hammer 2a. While the cost of constructing the sleeve hammer 2a, and, therefore, the cost of constructing the whole device after the manner seen in Figure 9, is 25 substantially greater than that of the structure seen in Figure 1, the operation will be substantially identical.

The hammer is adapted for almost innumerable uses, such as the freeing of stuck 30 valves, removal of small gears and pulleys, including timing gears and sprockets, the removal of rusted brake cam rods, the withdrawal of shackle bolts, the detaching of main bearing caps, and practically an endless 35 list of other devices. When freeing up-stuck valves, particularly of the overhead type, the jaw or part made up of prongs 5 and the connection therebetween is placed under the spring retainer between two of the 40 helices of the spring, and an up-thrust is imparted to the sleeve hammer 2, which, on striking the knob or shoulder 3, delivers a lifting blow on the valve. If the valve is not released, the blow is repeated until the valve 45 returns to its normal position, and if the valve then shows a tendency to stick, repeating the hammer blow action under the conditions stated will cause the valve stem to free itself in the guide and further difficulty with the valve will cease. With valves 50 of the L-head type of motors, the jaw of the present improved slide hammer is inserted under the head of the valve, and the operation is then carried out as just stated. To remove small gears or pulleys, the generator, 55 starter, distributor, or other mechanical part is firmly held as in a vise, and the jaws are inserted behind the part being removed, and then the hammering operation is carried out 60 until the gear or pulley is detached. In removing timing gears and sprockets, or any other parts which must be withdrawn accurately axially, it is desirable, and, in most instances necessary, to rotate the hammer 65 from one side of the part to the other between

alternating blows, and in this way the withdrawal movement is kept substantially uniform. To remove rusted brake cam rods, the car wheel is removed, and the brake cam 70 preferably saturated with a good solvent oil, and then the jaws of the hammer are introduced behind the cam and the withdrawal movement accomplished, as above stated. Shackle bolts can be removed through the oil doorways commonly provided in the running board splash apron though the bolts are not thus accessible to the ordinary hammer or two previously provided instruments. In removing engine main bearings which are 75 embedded or of the flush type, two of the bolts removed from the pan should be threaded firmly into each part, and the jaws of the hammer should then be introduced back of the head of the first one of the bolts and then the other alternately while delivering hammer blows successively so that the cap will be slipped out of the socket in a straight line. Many other advantageous uses exist for the 80 present improved hammer, and others will be found from time to time.

The jaw 5, as clearly seen in Figure 1, is 85 preferably approximately one-fourth as thick as the thickness of the shank or rod 1, and it is especially desirable that a comparatively thin jaw be provided, as shown, to enable access between gears and other places where the clearance is reduced or otherwise very slight.

In Figures 6, 7, and 8 the same identical parts are illustrated as above described, and are, therefore, given the same reference numerals with the understanding that the foregoing description applies equally except that the rod 1 is made in two sections which are rendered easily detachable but firmly and effectively locked together during use. The jaw 5 with its lateral loop 4 becomes a detachable tool by forming the rod 1 into separable sections joined by having each section provided with a recess 7 and an outstanding 100 portion 8 adapted to snugly fit the recess 7 of the other section. The parts 7 and 8 are readily brought laterally together and are 105 preferably proportioned to have a very snug, tight fit. A locking sleeve 9 is preferably slipped onto the main portion of rod 1 before the interlock 7 and 8 is brought together, and when the interlock is brought together, so 110 that the tool is thus connected to the rod, the sleeve 9 is moved down over the joint between the two sections, as clearly indicated in Figure 6, and the sleeve thus effectively serves to supplement the connection and lock the parts together so that the resulting structure 115 is adapted for all purposes to function as described with respect to the structure seen in Figure 1. In fact, the parts function thus and also provide certain additional important advantages. For instance, if the operator of 120 the structure seen in Figure 1 desires to use 125

his hammer for tamping purposes, as for tapping a gear back onto a shaft where the driving fit requires some substantial pressure, he may place the flat, exposed face of the jaw 5 against the gear and then strike the curved part of the loop 4 with the end of sleeve hammer 2. This, of course, delivers a reverse stress from that generally intended for the functioning of the hammer, or, in other words, it delivers a direct hammering stress, and this sometimes is desired as a matter of avoiding the necessity for other tools for that purpose. When such tamping action is needed with the structure as seen in Figure 6, the sleeve 9 will move under the tapping of sleeve hammer 2 down into a seated position against the curve of the loop 4 and will remain there offering its upper end as a circular shoulder or seat against which the sleeve hammer 2 may act, and thus the tamping blows may be delivered effectively at as high pressure as required without danger of injuring the parts. The movement of the sleeve 9 can be avoided by placing the sleeve in the first place down against the curve where it can move no further outward toward the jaw, and the sleeve of course is of sufficient length to still remain overlapping the upper end of the coupled joint between the two sections of the rod.

It will be readily observed that by the provision of a detachable coupling several advantages are gained. Should one of the prongs of jaw 5 break, or any other injury occur to the tool part, a new jaw or tool may be supplied and it is also feasible to apply other forms of tools, such as may be found desirable, for use in connection with the action of the slide hammer either for direct hammer blows or for retracting hammer blows.

Furthermore, there is a direct combinative relation between the integral knob or shoulder 3 and the detachable feature of the jaw 5, because by virtue of the jaw 5 being made detachable, that part of the rod 1 on which the head 3 is to be formed will be introduced into the swaging machine or header, and the shoulder or knob 3 formed up without having the sleeve hammer 2 present, and also in the absence of the sleeve 9 and the jaw 5. These parts may readily be applied after the swaging operation. Furthermore, with this detachable coupling arrangement, the tool or jaw may be readily differently tempered from the tempering of the main portion of the rod, according to the work to be performed.

It will be readily understood that the sleeve 9 is held frictionally against displacement, being proportioned to snugly engage the rod 1, but to be capable of movement when tapped with a hammer. An appropriate detent to prevent creeping of the sleeve 9, not illustrated, may be provided, (such

as a bearing ball embedded in the rod and outstanding laterally thereof sufficiently to frictionally resist but not prohibit driven movement of the sleeve) but my observation covering thousands of hammers provided with the sleeve 9 is that the sleeve under all ordinary conditions of use remains in place under its own frictional engagement with the rod itself without the requirement of a supplementing detent.

This application is a continuation in part of my co-pending application Serial No. 466,288, filed July 7, 1930, this application being presented to enable a full disclosure and a more complete and accurate showing of matters partly omitted from and partly insufficiently set forth in my said co-pending application, which matters were part of my invention and successfully used by me in the United States prior to the filing of said co-pending application and omitted from and insufficiently shown therein because of my unfamiliarity with the requirements for detailed disclosure in a patent application.

What is claimed is:—

1. In slide hammer construction, the combination of a rod having a stop to receive a hammer blow, and a hammer slidably mounted on the rod to deliver such hammer blow, the hammer being free to move angularly or rotate relative to the rod, and the sliding engagement between the hammer and rod being limited to spaced lines of contact.
2. The combination as claimed in claim 1 wherein one of the two parts is formed with a plurality of edges providing the said lines of contact.
3. The combination as claimed in claim 1 wherein the hammer is a sleeve surrounding the rod.
4. The combination as claimed in claim 1 wherein the hammer is a sleeve surrounding the rod and one of the parts is provided with spaced edges outstanding to contact with the other.
5. The combination as claimed in claim 1 wherein the hammer is a sleeve surrounding the rod and having a curved surface for the bore through which the rod extends, and the rod being provided with longitudinal edges adapted to be engaged by said curved surface.
6. In slide hammer construction, the combination of a polysided rod having a stop, and a sleeve hammer mounted on the rod to cooperate with said stop, the bore of the sleeve hammer being formed with a curved surface presented to the edges of the rod produced by the meeting of its multiple sides.
7. The combination as claimed in claim 1 wherein the rod and hammer are tempered sufficiently to resist wear along the lines of contact and to proportionally reduce frictional engagement along said lines.
8. In slide hammer construction, the combination of a rod having a stop to receive a

hammer blow and a sleeve hammer slidingly and rotatively engaging the rod to move along the same to deliver a hammer blow to said stop, one of the adjacent surfaces being 5 tween the hammer and the rod being circular transversely of the rod and the other being polysided to present spaced longitudinal edges of contact.

10 In testimony whereof I affix my signature.
HARRY GAIL KREIS.
